Primary Examiner — Brian N Vinson

(57) **CLAIM**

The ornamental design for a tray, as shown and described.

DESCRIPTION

FIG. 1 is a top, front, right perspective view of a tray our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines represent unclaimed portions of the tray, and no claim is made to the dimensions between broken away edges.

1 Claim, 4 Drawing Sheets---
